UNITED STATES PATENT OFFICE.

JOHN BLAIR, OF BROOKLYN, NEW YORK.

FOUNTAIN-PEN.

SPECIFICATION forming part of Letters Patent No. 773,847, dated November 1, 1904.

Application filed April 16, 1904. Serial No. 203,452. (No model.)

To all whom it may concern:

Be it known that I, JOHN BLAIR, a citizen of the United States, residing at Brooklyn, in the county of Kings and State of New York, 5 have invented new and useful Improvements in Fountain-Pens, of which the following is a specification.

In the writing-pens in which a supply of ink is carried in a reservoir in the barrel of 10 the pen and intended to be fed down to the pen-point in the act of writing there is still more or less difficulty in regulating the "feed" of the ink to the exact demand. There is also a liability to "flooding" and to the exudation 15 of the ink through the joint connecting the pen-section with the barrel. This invention is designed to remedy these defects. A great desideratum in pens of this class is a means for filling the ink-reservoir in the pen-barrel 20 without employing a separate filler and without removing the pen-section. My present invention includes a very simple device for effecting this object.

The accompanying drawings fully illustrate 25 the invention, its various features being referred to by letters, similar letters denoting corresponding parts in the several views.

Figure 1 is a side view of the pen, partly in section and with the cap on the rear end. Fig. 30 2 is an enlarged plan of a cross-section of the nozzle or pen-section on line xx of Fig. 1. Fig. 3 is an enlarged plan of a cross-section on line yy of Fig. 1, and Fig. 4 is an enlarged cross-section on line zz of Fig. 1.

35 The letter A designates the barrel of the pen, which incloses the reservoir holding the supply of ink, and a is the removable threaded plug at the rear end of the barrel.

B indicates the pen-section of a fountain- 40 pen or, as shown in the drawings, the point-section of a stylographic pen. It has a threaded end b to engage the inner threaded end of the barrel A. This point-section is provided with an exterior annular recess b' at the base 45 of the conical point b^2 and with a recess b^3 between its middle part and its rear threaded end b . An air connection b^4 is made across these threads to connect the recess b^3 with the reservoir in the barrel.

50 One or more air-ducts b^5 are made length-

wise from the recess b' through the pen-section to the recess b^3 . A continuous air connection is thus established between the exterior recess b' and the ink-reservoir by which a uniform air-pressure is maintained and flooding and leakage are prevented. 55

b^6 is the ink-duct through the point-section, in which the feed-bar b^7 is located.

On the threaded rear end of the barrel A is the threaded plug a already mentioned. The 60 threads and part of the stem of this plug are cut off at one or more places to form an air-passage a^8 when the plug is partly removed.

C is a cap having a small vent-hole c , preferably through its otherwise closed end. 65 This cap is employed to cover and protect the nib of the pen when the pen is not in use and is also made to fit evenly and snugly over the rear end of the barrel, covering, of course, the plug a . 70

In order to fill the ink-reservoir, the plug a is unscrewed about a half-turn or just sufficient to allow the passage of air through the channel a^8 . The cap C is then put on and pressed down its full length. The nib or point 75 of the pen is then inserted in the ink, when by covering the hole c with the finger and slowly drawing the cap off the ink will be drawn up by suction into the ink-reservoir. The plug is then screwed down tightly and 80 the operation of filling the pen is completed.

In order to prevent a failure of the tractive force by reason of imperfect joining of the inner surface of the cap with the barrel, either 85 by the stretching of the cap or defective construction, I form a groove D around the body A near its rear end, and insert in said groove a collar or packing d , of linen, wax, or other suitable substance, which will insure an air-tight connection between the cap and the barrel. 90 If necessary, there may be two or more of these collars provided.

Having now described the invention and the manner of using it, what I claim, and desire to secure, is—

1. In a fountain-pen a point-section having a body portion and an interior threaded portion provided with a longitudinal air-channel, said interior portion having a recess between said body portion and said threaded portion 95 100

and said body portion having an exterior annular recess and air-holes connecting said annular recess with said recess on said interior portion, substantially as herein set forth.

- 5 2. In a fountain-pen whose point-section is provided with an internal annular recess, a terminal threaded part on said point-section provided with an air-channel, an exterior annular recess at the forward part of said point-
10 section and air-ducts connecting said exterior

recess with said internal annular recess as herein described.

In testimony whereof I have signed my name to this specification in the presence of two subscribing witnesses.

JOHN BLAIR.
